(57) **CLAIM**

The ornamental design for a carrier for mounting an antenna assembly in a utility meter enclosure, as shown and described.

DESCRIPTION

FIG. 1 is a perspective top view of a carrier for mounting an antenna assembly in a utility meter enclosure.

FIG. 2 is a front view of the carrier for mounting an antenna assembly in a utility meter enclosure of FIG. 1.

FIG. 3 is a rear view of the carrier for mounting an antenna assembly in a utility meter enclosure of FIG. 1.

FIG. 4 is a right side view of the carrier for mounting an antenna assembly in a utility meter enclosure of FIG. 1.

FIG. 5 is a left side view of the carrier for mounting an antenna assembly in a utility meter enclosure of FIG. 1.

FIG. 6 is a top view of the carrier for mounting an antenna assembly in a utility meter enclosure of FIG. 1.

FIG. 7 is a bottom view of the carrier for mounting an antenna assembly in a utility meter enclosure of FIG. 1.

FIG. 8 is an exploded view of the carrier for mounting an antenna assembly in a utility meter enclosure of FIG. 1; and, FIG. 9 is a perspective environmental view of the carrier for mounting an antenna assembly in a utility meter enclosure of FIG. 1, shown positioned within a utility meter enclosure that is mounted on a utility meter.

The broken lines show unclaimed subject matter only and form no part of the claimed design. The dash-dot broken lines represent unclaimed boundaries of the claimed design.
